(57) CLAIM

I claim the ornamental design for a grasp-enhancing band for a drinking vessel, as shown and described.

DESCRIPTION

FIG. 1 is a top plan view of a grasp-enhancing band for a drinking vessel showing my new design.

FIG. 2 is a top, front perspective view thereof.

FIG. 3 is a front view thereof, the shot glass is shown in broken lines for illustrative purposes only and forms no part of the claimed design.

FIG. 4 is a front view thereof, the rocks glass is shown in broken lines for illustrative purposes only and forms no part of the claimed design; and,

FIG. 5 is a front view thereof, the beer glass is shown in broken lines for illustrative purposes only and forms no part of the claimed design.

It should be noted the grasp-enhancing band has certain curved surfaces as depicted in the drawing disclosure.
